UNITED STATES PATENT OFFICE.

ISIDOR KITSEE, OF PHILADELPHIA, PENNSYLVANIA.

ELECTRIC TRANSMISSION OF INTELLIGENCE.

No. 918,866.

Specification of Letters Patent.

Patented April 20, 1909.

Application filed June 10, 1908. Serial No. 437,636.

To all whom it may concern:

Be it known that I, ISIDOR KITSEE, a citizen of the United States, residing in the city of Philadelphia, county of Philadelphia, and 5 State of Pennsylvania, have invented certain new and useful Improvements in Electric Transmission of Intelligence, of which the following is a specification.

My invention relates to the transmission 10 of alternating or fluctuating electric currents as for signaling and power purposes, but particularly for the transmission of intelligence, as by telephony or telegraphy, and relates particularly to the transmission of signals, 15 power, or intelligence over long distances.

My invention resides in transmitting and receiving apparatus associated with a line conductor comprising conductively independent conductors associated throughout 20 their lengths, or a substantial part of their lengths, in inductive relation, there being an associated conductor in inductive relation with said first mentioned conductors and consisting of a conductor either similar to said 25 first mentioned conductors, or disposed as a sheathing or covering for said first mentioned conductors, connections to earth being made at a plurality of points along said associated conductor.

30 The conductively independent and inductively related conductors are preferably twisted together, while the associated conductor, in the form of a wire, sheath, wrapping of any sort, or a braid, is in inductive relation throughout the line with the first mentioned conductors and connections made from said associated conductor to earth at a plurality of points, occurring preferably at uniform intervals along the line. In some 35 cases, the associated conductor, as when it is a wire, may be twisted with the other conductors, or disposed in similar manner to them, if not twisted. And when the associated conductor takes the form of a braid, or 40 other sheath or wrapping, it may be disposed to partially or entirely surround or embrace the inductively related or twisted conductors. But, in all cases, one or more connections 45 are made from the associated conductor to earth at preferably uniform intervals along the line.

By the arrangements above described, I have found that the transmission of alternating or fluctuating currents is greatly improved, particularly by the connections to

earth from the associated conductor at practically equally recurring intervals.

For an illustration of some of the forms my invention may take, reference is to be had to the accompanying drawing, in which:

Figure 1 is a diagrammatic view of a telephone system in which three insulated conductors are twisted together, the third or associated conductor serving as a return, and having a plurality of connections to earth. 65 Fig. 2 is a diagrammatic view of a telephone system in which the line conductor comprises a pair of conductively independent conductors twisted together, the associated conductor taking the form of a continuous or braided sheath, or other conducting wrapping, in inductive relation with the twisted line conductor, and having connections to earth, the earth serving as a return conductor. Fig. 3 is a diagrammatic view of a telephone system in which the line conductor 70 consists of a pair of conductively independent conductors twisted together, the associated conductor being a continuous or braided sheath, or other suitable wrapping, in inductive relation with the line conductor, such 75 sheath or wrapping serving as a return conductor, and a plurality of connections to earth from the associated conductor. 80

In Fig. 1, A, B, and C are insulated conductors twisted together throughout their entire lengths, or a substantial part of their entire lengths. They are thus conductively independent but inductively related. One of these conductors, as C, is used for a return conductor. Thus, at the left hand station there is connected between the conductors A and C the telephone receiver T and the secondary S of a telephone induction coil or transformer. In circuit with the primary P is the usual microphone M and battery b. At the right hand station, the apparatus is connected, however, between conductors B and C. And at a plurality of points, occurring preferably, though not necessarily, at uniform intervals, there are connections e to earth E. 95

While the conductor C is conductively connected to the conductor A through the telephone apparatus at the left hand station, and to the conductor B through the telephone apparatus at the right hand station, yet throughout the line the conductor C is conductively independent of A and B, but inductively related to them. The connec- 100 105 110 115

tions from the associated conductor C to earth at a plurality of points greatly improves the transmission.

While not limiting myself to any particular theory as to the reasons for this improved transmission, due to the earth connections from the associated conductor, it is my belief that the connections from the associated conductor to earth at a plurality of points serve to cause said associated conductor to act as a conductor of practically no resistance and of practically no self-capacity and of practically no self-induction. The more of these connections c from the associated conductor to earth E, within limits, the better will be the transmission; for if the connections to earth are at too great distances from each other the ohmic resistance of the associated conductor C between neighboring earth connections may be great enough to cause undesirable retardation.

The composite line conductor shown in Fig. 1 and comprising the insulated conductors A, B twisted together and associated with C, and the associated telephonic apparatus, corresponds with that shown in Fig. 3 of my prior patent No. 803,109. And while I have here shown the associated conductor C disposed as one of three twisted conductors, it is to be understood that the earth connections may be applied to the associated conductor when otherwise disposed as, for example, conductor C in Figs. 1 and 2 of my said prior patent, or when disposed in any other manner.

In Fig. 2, the telephonic apparatus at each station is the same as shown in Fig. 1, except that the return is through the earth E. In this case, the associated conductor C takes the form of a sheath of either continuous or discontinuous (as braided) conductor, partially or entirely surrounding or associated with the conductors A and B. Here the sheath C may be considered also as a return conductor since there is a path from the terminals of the secondaries S, S through the earth to the terminal earth connections c, c. Or, the secondaries S, S may be connected directly to the sheath or associated conductor C, as shown in Fig. 3. Indeed, the arrangement shown in Fig. 3 is the preferred one, particularly in view of the fact that the terminal earth connections c are at a substantial distance from the ends of the sheath. It is very generally the case that in situations or communities where the terminal instruments are located, there are present earth currents due to various causes, and these earth currents may cause disturbances upon the telephone or signaling circuit where the connections are made to earth at the terminal instruments. By connecting the terminal instruments to the sheath or associated conductor, however, in place of connecting them directly to earth, and where

the terminal connections from associated conductor to earth are at a substantial distance from the ends of the sheath or associated conductor, these undesirable effects from earth currents and the like are entirely eliminated. In all cases, however, whether the associated conductor be twisted with the line conductors or not, it is throughout the line insulated from the line conductors, but associated inductively therewith, and earth connections made at a plurality of points.

In the cases of Figs. 2 and 3, where the sheaths or associated conductors C will in most cases have a smaller ohmic resistance per unit of length than the associated conductor C of Fig. 1, the connections to earth may be fewer, that is, disposed at greater intervals along the line.

The connections c from the associated conductor to earth are preferably direct and of relatively low resistance.

The term "sheath" as used herein is generic and includes any continuous or discontinuous wrapping or covering either partially or entirely surrounding or embracing the line conductors, which are conductively independent and inductively related, and includes also a conductor or conductors of whatever shape or form disposed either parallel or spirally with respect to the composite conductor comprising conductively independent conductors in inductive relation.

While I have shown in the drawings only telephonic apparatus associated with the line conductors, it is to be understood that alternating or fluctuating current generating and absorbing apparatus may be so associated; or, that telegraphic or other signaling apparatus may be so associated.

What I claim is:

1. In a system for the transmission of varying electric currents, a line comprising conductively independent conductors disposed in inductive relation with respect to each other, an associated conductor in inductive relation with said conductors, and a connection from said associated conductor to earth.

2. In a system for the transmission of varying electric currents, a line comprising conductively independent conductors disposed in inductive relation with respect to each other, an associated conductor in inductive relation with said conductors, and a plurality of connections from said associated conductor to earth.

3. In a system for the transmission of varying electric currents, a line comprising conductively independent conductors disposed in inductive relation with respect to each other, an associated conductor disposed in inductive relation with respect to said conductors, and a plurality of connections from said associated conductor to earth at substantially equally recurring intervals.

varying electric currents, three conductors serially connected and also in inductive relation to each other throughout a substantial portion of their lengths, and a plurality of 5 connections from one of said conductors to earth.

20. In a system for the transmission of varying electric currents, three conductors serially connected and in inductive relation 10 with respect to each other throughout a substantial portion of their lengths, two of said conductors being twisted together, and a plurality of connections from the third conductor to earth.

15 21. In a system for the transmission of varying electric currents, two conductors in inductive relation with respect to each other throughout a substantial portion of their lengths and connected in series with 20 each other by their sheath, and a plurality of connections from said sheath to earth.

22. In a system for the transmission of varying electric currents, conductors twisted together throughout a substantial portion

of their lengths, a sheath inclosing said 25 twisted conductors, said twisted conductors and sheath being in inductive relation with respect to each other, said sheath being serially connected between said twisted conductors, and a plurality of connections from 30 said sheath to earth.

23. In a system for the transmission of varying electric currents, a line extending between stations and comprising conductively independent conductors disposed in 35 inductive relation with respect to each other, an associated conductor in inductive relation with said conductors, and a plurality of connections between stations from said associated conductor to earth. 40

In testimony whereof I have hereunto affixed my signature in the presence of the two subscribing witnesses.
